UNITED STATES PATENT OFFICE.

DAVID FERZACCA, OF LOGAN, WEST VIRGINIA.

NON-REFILLABLE BOTTLE.

1,300,713.

Specification of Letters Patent. Patented Apr. 15, 1919.

Application filed March 25, 1918. Serial No. 224,601.

To all whom it may concern:

Be it known that I, DAVID FERZACCA, a citizen of the United States, residing at Logan, in the county of Logan and State of West Virginia, have invented certain new and useful Improvements in Non-Refillable Bottles, of which the following is a specification.

This invention relates to non-refillable bottles, and more particularly to a bottle which is so constructed that it cannot be emptied without first being broken, thus preventing refilling of the bottle without knowledge of this fact by the purchaser.

One of the main objects of the invention is to provide a bottle of the character stated of simple construction and operation in which the discharge or exhaust openings for the contents of the bottle are restricted to such an extent that the fluid cannot be removed from the bottle without first breaking a portion thereof so as to admit air into the bottle as the fluid is drawn therefrom. A further object is to provide a bottle the neck of which is provided with a plurality of superposed web members extending completely across the same, these web members being provided with restricted openings arranged in staggered order, these openings being of such size as to permit discharge of the contents of the bottle when air is admitted into the interior thereof, but serving to effectually prevent discharge of the contents of the bottle until air is admitted at some other point. A further object is to provide a bottle the discharge opening through the neck of which is restricted for the purpose set forth, the base of this bottle being provided with an easily frangible member which may be removed so as to admit air above the contents of the bottle when the bottle is inverted for discharging the contents therefrom. Further objects will appear from the detailed description.

In the drawings:

Figure 1 is a central vertical section view of a bottle constructed in accordance with my invention.

Fig. 2 is a section taken substantially on line 2—2 of Fig. 1.

This bottle may be of any usual or preferred shape or construction and is provided with a body 1 at the upper end of which is provided the restricted neck 2. A plurality of superposed webs 3 are formed integral with neck 1 and extend completely across

the same. Each of these webs is provided with a restricted opening 4, the openings being arranged in staggered order. These openings are comparatively small so that, when the bottle is tilted or inverted, free access of air to the interior of the same is not permitted. This results in preventing the escape of the fluid from the bottle. By having the webs 3 provided with the staggered restricted openings 4, removal of the contents of the bottle by inserting a tube into the same for the admission of air, or for removing the fluid by suction, is prevented, the web members 3 constituting, in effect, baffles, which effectually prevent the insertion of such a tube.

To remove the contents of the bottle, it is necessary to provide means for admitting air into the interior of the body 1. For this purpose, I provide a downwardly directed conical member 5 at the center of base 6 of body 1, the central portion of this base being raised to provide a central recess 7 to accommodate member 5. A small knob 8 or bead is provided at the tip of member 5, and a shallow groove 9 is formed adjacent the inner end of this knob. This groove or channel weakens the glass adjacent the inner end or base of knob 8 so that, by grasping this knob, it may be readily broken away from the tip of member 5 thus providing an opening through which air may readily flow into the interior of the body above the contents thereof, when the bottle is tilted so as to discharge the contents. By this arrangement, the contents of the bottle may be readily discharged in the usual manner. However, to effect this discharge of the contents of the bottle, it is necessary to break the knob 8 off of the tip of member 5, the opening being subsequently closed by means of a cork or other suitable means if but a portion of the contents of the bottle be removed at one time. It will be evident that the knob 8 cannot be put back in position after having once been broken off, and it therefore serves as an indication to the purchaser that the bottle has been refilled. In this manner, the person knows that when the knob 8 is missing the contents are not the original contents.

The upper end of neck 2 is normally closed by a cap 10 which is carried by a band 11 secured about the neck, the cap being hinged to this band and normally held in closed position by a wire spring 12. The spring and hinge constitutes a spring hinge

of standard construction which need not be further described in detail. Of course, any other suitable means can be employed for closing the end of the neck, the object being 5 to prevent entry of foreign materials into the neck of the bottle.

To fill this bottle the neck 2 may be placed in the fluid which it is desired to place in the bottle, after which the air is exhausted 10 from the interior of the bottle by a pump or in any other suitable manner. As the air is exhausted from the body 1, the liquid will be drawn into the same and, after the bottle has been filled in this manner, it may be 15 sealed by fusing the glass at the tip of member 5 so as to produce the knob 8, a suitable groove or channel being provided about the base of this knob by means of a file or in any other suitable manner so as to render 20 the end of member 5 readily frangible. When the bottle is in upright position, the member 5 and knob 8 will be positioned within the recess 7 so as to be effectually shielded and protected by the base of the 25 bottle.

The foregoing description and the draw-

ings have reference to what may be considered the preferred, or approved, form of my invention. It is to be understood that I may make such changes in construction 30 and arrangement and combination of parts, materials, dimensions, etc., as may prove expedient and fall within the scope of the appended claim.

Having fully described my invention, 35 what I claim as new and desire to secure by Letters Patent is:

A non-refillable bottle whose neck has means to prevent the admission of air during the pouring out of the contents, the base 40 of the bottle being raised to produce a recess and the top of the recess depending in conical form, the tip of the cone being closed by a solid knob having a groove around its neck, whereby the knob may be manually broken to vent the bottle when inverted.

In testimony whereof I affix my signature in presence of a witness.

DAVID FERZACCA.

Witness:

M. E. JONES.
